DIP NET FRAME

James W. Harvey, Lakeville, Conn.

Application March 2, 1950, Serial No. 8,281

Term of patent 14 years

(Cl. D31—4)

To all whom it may concern:

Be it known that I, James W. Harvey, a citizen of the United States of America, residing at Lakeville, county of Litchfield, State of Connecticut, have invented a new, original, and ornamental Design for a Dip Net Frame, of which the following is a specification, reference being had to the accompanying drawing, forming part thereof.

Fig. 1 is a plan view of a dip net frame showing my new design.

Fig. 2 is an edge view of the same.

Fig. 3 is an enlarged plan view of a fragment of the lower end of the upper part of the frame.

Fig. 4 is an enlarged plan view of the handle of the frame.

Figs. 5, 6, 7 and 8 are cross sectional views taken on the planes of the lines 5—5, 6—6, 7—7 and 8—8, respectively.

I claim:

The ornamental design for a dip net frame, as shown.

JAMES W. HARVEY.
